GRIP FOR SANITARY NAPKINS OR THE LIKE

Irvin S. De Woskin, St. Louis, Mo., assignor to Beltx
Corporation, St. Louis, Mo., a corporation of Missouri

Filed Oct. 18, 1963, Ser. No. 77,032

Term of patent 14 years

(Cl. D17—9)

FIG. 2.

FIG. 1 is a view in elevation of a grip for sanitary napkins or the like embodying my new design; and

FIG. 2 is an edge view of FIG. 1.

I claim:

The ornamental design for a grip for sanitary napkins or the like, substantially as shown.
